UNITED STATES PATENT OFFICE.

LARNED S. WHITNEY, OF FISKDALE, MASSACHUSETTS.

METHOD OF MAKING RAKES, FORKS, AND THE LIKE.

1,142,001.

Specification of Letters Patent.

Patented June 8, 1915.

Application filed July 10, 1913. Serial No. 778,236.

To all whom it may concern:

Be it known that I, LARNED S. WHITNEY, a citizen of the United States, residing at Fiskdale, in Worcester county, in the State 5 of Massachusetts, have invented a new and useful Method of Making Rakes, Forks, and the like, of which the following is a specification.

This invention relates to a method of 10 manufacturing all kinds of rake-like and fork-like implements, such as, for example, level-head rakes, curved-tooth rakes, bow-rakes, bow-braced rakes, gravel rakes, road rakes, asphalt rakes, hay forks, header forks, 15 manure forks, spading forks, barley forks, digging forks, coke forks, coal forks, stone forks, ballast forks, tanners' forks, sluice forks, ensilage forks, oyster forks, beet forks, potato hooks, stone hooks, manure hooks, 20 and clam hooks.

The object of my invention is to furnish a simple and economical method of manufacturing the above mentioned implements and the like which will produce superior 25 and durable products.

The accompanying drawings show the condition of the material operated upon after the successive steps of a method involving my invention as applied to the man- 30 ufacture of a rake.

Figure 1 is a plan view of the stock; Fig. 2 is a vertical section of the stock on line 2-2 of Fig. 1; Fig. 3 is a plan view of the stock after forging; Fig. 4 is a horizontal section on the line 4-4 of Fig. 3; Fig. 5 is a vertical section on line 5-5 of Fig. 3; Fig. 6 is a perspective view of the stock after forging showing a section on line 5-5 of Fig. 3; Fig. 7 is a plan view of the 40 stock after severing; Fig. 8 is a plan view of the stock after partial straightening of the tines; and Fig. 9 is a plan view of the final stock after the shaping of the tines.

In the preferred method of carrying out 45 my invention, I take a substantially flat strip or plate of steel or other metal, which may be termed the stock. The stock is preferably first heated. It is then pressed between dies and thus forged. The dies are so shaped 50 that when the stock is pressed between them the portion of the material which is not to be used as the head and tines of the rake is pressed down or off-set from the portion of the material which is to be so used, which is 55 hereinafter referred to as the blank. The upper die has a raised portion correspond- ing in shape and size to the portion of the stock which is to be pressed down or off-set, while the lower die has a raised portion corresponding to the size and shape of the 60 blank. I have referred to the upper and lower dies and the pressing-down of a portion of the stock merely for convenience, and I do not desire to be limited to drop-forging the stock while it is in a horizontal posi- 65 tion. It is obvious that the stock may be held vertical and the dies pressed against it sidewise or in any other direction without departing from my invention.

Figs. 3, 4, 5, and 6, show the condition of 70 the stock after forging. In Fig. 3, 1 represents the blank or portion of the stock from which the head and tines of the rake are to be made. 2 represents the portion of the stock which is off-set in the forging. 75

The dies used in the forging are prefer- ably so shaped that the off-set portion of the stock 2 shall be of a shape suitable to be used as a blank for the head and tines of another rake. This may be done by so form- 80 ing the dies that the portions 4 of the part 2 which are between the tines 5 of portion 1 shall form tines intermeshing with the tines 5. If this is done, there is no considerable waste of metal, as the off-set portion 2 and 85 the portion 1 use substantially all the metal of the stock.

The movement of the dies is preferably so regulated that the distance which they move toward each other after they have 90 both come in contact with the surface of the stock is slightly less than the thickness of the stock so that the portion of the stock which is off-set is not severed from the blank, the two portions remaining connect- 95 ed by a thin sheet of metal 3. The two portions are then severed, preferably by press- 100 ing the forged stock between two flat dies so as to force the two portions back toward the same plane, thus severing the metal at 3 (Fig. 6). This gives more satisfactory re- 105 sults than forging and severing by a single operation, and I accordingly prefer to carry out the process in this way. The condition of the material after this step is shown in Fig. 7. The next step consists in straighten- 110 ing and shaping the tines of the blank or blanks which have been formed, thus forming one or more rakes or forks. The portions 1 and 2 may be first separated, and the tines then straightened and shaped in any suitable way. It is, however, preferable to

straighten and roll or draw out all the tines of a blank simultaneously.

A preferred way of straightening the tines in case blanks have been formed with 5 intermeshing tines which are wholly or in part oblique to the head portions of the blanks consists in first straightening or partially straightening the tines while the blanks are in position with their tines intermeshing, as shown in Fig. 7, by pressing upon one end of each blank in such a way as to cause relative longitudinal displacement of the blanks in such direction and to such extent that the tines are brought from 10 an oblique position to a position more nearly perpendicular to the head portions of the blanks. Thus, blank 1 is forced to the right of Fig. 7, while blank 2 is held stationary or forced to the left. The blanks 15 may in some instances be advantageously heated before straightening them, and in order that the blank may not be bent or sprung laterally, retaining means should be provided, as, for example, holding dies having 20 flat surfaces like those used to sever the blanks. With the form of tines shown, the result of the operation described is to partially straighten the tines of each blank. The shape of a blank after this operation is 25 shown in Fig. 8. After partial or complete straightening of the tines by longitudinal displacement of the blanks, the tines are shaped or completely straightened and shaped by any suitable means.

30 The method described has many advantages over the method of making rakes by stamping out the blanks. Stamping involves the use of sharp-edged dies which cut out the metal. This method of making the 35 blanks adds nothing to the strength of the metal of the tines, so that the tines are likely to break off when an implement made by this method is used. My method of drop-forging the blanks strengthens the metal 40 of the tines and therefore renders them strong and durable. My preferred method of severing the blanks by pressing them together breaks the metal cleanly and leaves no fin at the edge of the severed portion.

45 50 Stamping dies are very expensive to manufacture and to keep in condition, for they must be very accurately adjusted and their edges must be kept sharp if they are to cut satisfactorily. The dies used in forging in 55 my method are not required to do any cutting, can therefore be made comparatively cheaply, and do not readily wear out. This is particularly so when the preferred method of severing the blanks by pressing the forged 60 stock between flat dies is used. My method is therefore much more economical than stamping.

The method of my invention has peculiar and special advantages when used in connection with rake blanks having intermesh-

ing tines. Previous to my present invention, it has not been practicable to make two rake blanks with intermeshing tines from a single piece of stock except by stamping or cutting one blank from the other. Therefore, 70 rakes which have been made from intermeshing blanks have been comparatively expensive and of an inferior quality, with tines that are comparatively easily broken. It is generally recognized that to be useful 75 and durable, the tines of a rake should be forged. The use of my method in connection with blanks with intermeshing tines provides for the manufacture of rakes and forks with forged tines at low cost. 80

Although I have used a rake to illustrate the process, the application of my invention to other tined implements will be plain from the foregoing.

I claim:

1. A process of manufacturing tined implements comprising pressing on opposite sides of a piece of stock with dies each shaped to cover a blank and so arranged that the tine portions of one blank intermesh with the tine portions of the other, continuing such pressure until the two blanks are off-set with respect to each other, separating said blanks, and shaping the blanks thus obtained. 95

2. A process of manufacturing tined implements comprising pressing on opposite sides of a piece of stock with dies each shaped to cover a blank and so arranged that the tine portions of one blank intermesh with the tine portions of the other, continuing such pressure until the portion of the stock forming one blank is off-set and almost, but not quite, severed from the portion of the stock forming the other 100 blank, pressing said portions back toward the same plane, thereby severing them, and shaping the blanks thus obtained. 105

3. A process of manufacturing tined implements, comprising severing a piece of 110 stock into two blanks with intermeshing tine portions oblique to the head portions of said blanks, relatively longitudinally displacing the blanks so as at least partially to straighten said tine portions, and shaping 115 said blanks.

4. A process of manufacturing tined implements, comprising severing a piece of stock into two blanks, each blank having tine portions at least in part oblique to the 120 head portion of said blank and intermeshing with the tine portions of the other blank, pressing upon opposite ends of said blanks so as to cause relative longitudinal displacement of the blanks, whereby said tine portions are at least partially straightened while holding said blanks against laterally bending, and shaping said blanks. 125

5. A process of manufacturing tined implements, comprising pressing on opposite 130

sides of a piece of stock with dies each shaped to cover a blank comprising a head portion and tine portions at least in part oblique to its head portion and so arranged that the tine portions of one blank intermesh with the tine portions of the other, continuing such pressure until the two blanks are off-set with respect to each other, severing said blanks, pressing on opposite

ends of said blanks so as to cause a relative longitudinal displacement of said blanks whereby said tine portions are at least partially straightened, and shaping said blanks.

LARNED S. WHITNEY.
